UNITED STATES PATENT OFFICE.

ABRAHAM M. BAKERMAN, OF NEW YORK, N. Y.

NECKTIE.

1,349,486.

Specification of Letters Patent. Patented Aug. 10, 1920.

Application filed August 22, 1919. Serial No. 319,141.

To all whom it may concern:

Be it known that I, ABRAHAM M. BAKERMAN, a citizen of the United States, and a resident of the city of New York, county of New York, and State of New York, have invented a new and Improved Necktie, of which the following is a full, clear, and exact description.

This invention relates to neckwear and particularly to neck ties of what is known as the four in hand model.

A purpose of this invention is to disclose a self tied neck wear manufactured to resemble a tie as usually worn and tied on and around collars. A feature resides in the ready made and ready to wear fold or knot which constitutes the head piece adapted to fit up under the collar.

An object is to produce a two piece tie comprising a tie head or knot, a fly, and a tie band, all parts so arranged that the tie may be quickly adjusted into place and securely held in service position. A feature resides in the tie knot or tie head which resembles a well executed and deftly arranged tie knot of fashion and style.

Drawings are presented to further substantiate my disclosure, and in Figure 1 is shown a front view of the complete tie.

Fig. 2 shows a rear view of the tie head or knot in part section with a cloth covering partly removed to show parts.

Fig. 3 illustrates a view taken on the line 3—3 of Fig. 2.

Fig. 4 shows a sectional view taken on the line 4—4 of Fig. 3.

Fig. 5 is a view of a clamping attachment carried on the back of the tie head or knot.

A neckwear apparel patterned according to the plan of this invention consists of a head piece made of pliable or yieldable material provided with a clamping attachment. A fly or streamer ribbon depends from the head piece, and a tie band is slidably associated with the head piece in order to draw the tie into service and closed position with the wearer's collar.

Referring more in particular to the drawings for a more detailed description, there is pointed out the head piece 7 made of rubber or other appropriate pliable material shaped down to approximate the size and contour of the usual tie form or knot made when a four in hand tie is tied into a collar. A pair of tie band tube guides

8 are vulcanized into the head. These parts may be made of very light tubing, or if desired the head piece may be molded with the tube openings made therein without the 60 guide or liner 8.

A clamping attachment, for engaging the tie band and holding said band taut, is made up of a plate 9 integral with a bracket 10 spaced from the plate. The lower end 65 of the bracket is provided with integral and lateral tabs 11 which are bent around the lower part of the head piece and clamped thereon to assist in holding the clamping attachment on the head piece. A pair of 70 clamp arms, comprising a serrated head 14 and press ends 15, are disposed between the plate 9 and spaced bracket 10; and are fulcrumed on a pin 16 secured in the plate and bracket. A spring, comprising the two 75 upstanding parts 17 carried on an integral coil, is confined on the pin 16 with the upper ends compressively engaging the clamp arms to press them normally outwardly against upturned stops 18 integral 80 with the plate 9. The plate is made with openings which register with and receive thereinto the ends of the tubes 8, and the contacting parts may be soldered or otherwise secured together. Each serrated head 85 lies across the opening of the tube passage and is limited from further lateral movement by the stops 18. By pressing on the press ends 15 of the clamp arms the serrated heads can be moved out of engagement with the stops 18 and from over the tube openings. The Fig. 5 shows a complete assembly of the clamp attachment joined with the two guide tubes, the structure being separated from the rubber head piece. 95

The clamp attachment is applied to the rear face of the rubber head piece and the tabs bent and shaped around the head as illustrated. The upper portion is secured to the head by joining the plate and tubes. A 100 silk fabric covering 20 is next sewed over the assembled clamp attachment and head piece to form the ornamental finish necessary to neckwear and neck ties for dress purposes. Small holes may be provided in the 105 metal parts to facilitate the sewing of the cloth to the frame and other parts. The assembled head and clamp attachment is completely covered excepting the two tube openings in the rear, which are left open to receive a tie band as later described. 110

A tie band 21 consists of a long ribbon or

band associated with the finished head or tie knot. Each end of the band has attached thereto a metallic end piece 22, and a corrugation or kink 23 formed in one of the end pieces. The end pieces should be of flexible thin plate steel and be covered over and concealed within the fabric ends of the tie band. The tie band is inserted in tie knot by introducing each end piece 23 through the tubes 8 which allows the band to loop around as shown in Fig. 1 and permits the tie band ends to hang down from the tie knot.

10 The tie pendant or streamer is of usual design and is attached to the tie knot in an approved manner. This streamer 24 covers the tie band ends and conceals them from view.

15 The wearer grasps the tie knot or head piece between his thumb and forefinger and 20 presses inwardly until the serrated heads are disengaged from the stops 18 and until the tie band slips freely through the tie knot to enable the wearer to adjust the tie to his collar. The release of pressure on the sides 25 of the tie knot drops the serrated heads into engagement with the tie band and against the stops 18 which firmly clamps the tie band in fixed position in a collar and around the wearer's neck. The corrugation 23 keeps 30 the tie band attached to the tie knot while one end of said band is removed to place it through a collar.

The tie is worn as is the usual tie. The wearer does not have to trouble with the constant tying of the knot. The knot may 35 be patterned after the approved style of the season, and the fabric tie material could, if desired, be renewed when worn old. The invention and tie as disclosed herein is fittingly gifted with the several advantages 40 of neatness and utility and presented to fulfil the want felt for an article of apparel of this class.

Having thus described my invention, what I claim as new and desire to secure by Letters Patent is as follows:

An attachment or accessory for neckties, comprising a straight bar, a transverse piece made on one end thereof, the upper end of the bar turned down in approximately parallel relation with the bar, openings made in the turned-down part, clamp legs with serrated ends pivoted between the bar and turned-down part with the serrations adapted to lie across the openings, a 55 head piece placed adjacent the attachment, said head piece having passages made therethrough and registering with the openings in the turned-down bracket, and the aforesaid transverse bar bent around the head 60 piece to hold the head piece and attachment together.

ABRAHAM M. BAKERMAN
